UNITED STATES PATENT OFFICE.

HENRY E. RUSSELL, OF NEW BRITAIN, CONNECTICUT, ASSIGNOR TO THE RUSSELL & ERWIN MANUFACTURING COMPANY, OF SAME PLACE.

DESIGN FOR AN ESCUTCHEON-PLATE.

SPECIFICATION forming part of Design No. 22,756, dated August 29, 1893.

Application filed August 7, 1893. Serial No. 482,618. Term of patent 7 years.

To all whom it may concern:

Be it known that I, HENRY E. RUSSELL, a citizen of the United States, residing at New Britain, in the county of Hartford and State of Connecticut, have invented and produced a new and original Design for a Door-Knob and Lock Escutcheon-Plate, of which the following is a specification, reference being had to the accompanying drawing, forming part thereof, of, in which the only figure is a perspective view of a knob and lock escutcheon-plate, showing my design, together with a knob of a harmonizing design.

A designates the body of the plate having the boss 2 which forms the knob escutcheon and the key hole 3 which forms the lock escutcheon. At each end of the plate there is

a series of club like ornaments 4, arranged side by side with their larger ends outwardly as shown. Inside of these ornaments 4 there is a transverse band 5 having a row of circular ornaments.

The design for the knob herein shown is made the subject of a separate application of even date herewith, Serial No. 482,617. 25

What I claim is—

The design for a knob and lock escutcheon plate substantially as herein shown and described.

HENRY E. RUSSELL.
